CHESS GAME BOARD

John A. Benson, Jr., Alta Loma, Calif. 91701

Filed Apr. 30, 1974, Ser. No. 465,567

Term of patent 14 years

Int. Cl. D21—10

U.S. Cl. D34—5 SS

FIG. 1

FIG. 2

FIG. 1 is a top plan view of my new design for a chess game board; and

FIG. 2 is an end view thereof.

The characteristic feature of my design resides in the four row player extensions each having the particular set of chess-men shown inscribed thereon and bordered by numerals and letters with the latter interposed between marginal triangles.

I claim:

The ornamental design for a chess game board, substantially as shown and described.
